US0D1002389S

(12) **United States Design Patent** (10) **Patent No.:** **US D1,002,389 S**
(45) **Date of Patent:** **** Oct. 24, 2023**

(54) **SIX-CELL BEVERAGE BOX**

- (71) Applicant: **Pratt Corrugated Holdings, Inc.**, Brookhaven, GA (US)
- (72) Inventors: **Shifeng Chen**, Newport News, VA (US); **Greg Sollie**, Sharpsburg, GA (US); **Jamie Waltermire**, Peachtree City, GA (US)
- (73) Assignee: **Pratt Corrugated Holdings, Inc.**, Brookhaven, GA (US)
- (**) Term: **15 Years**
- (21) Appl. No.: **29/895,791**
- (22) Filed: **Jun. 26, 2023**

(57) **CLAIM**

We claim the ornamental design for a six-cell beverage box, as shown and described.

DESCRIPTION

FIG. 1 is a front perspective view of a six-cell beverage box showing the claimed design with a telescoping portion positioned in an extended configuration.

FIG. 2 is a front elevation view thereof.

FIG. 3 is a rear elevation view thereof.

FIG. 4 is a left-side elevation view thereof.

FIG. 5 is a right-side elevation view thereof.

FIG. 6 is a top plan view thereof.

FIG. 7 is a bottom plan view thereof.

FIG. 8 is a plan view of the six-cell beverage box shown in a fully collapsed configuration.

FIG. 9 is a top perspective view of the six-cell beverage box shown in a partially collapsed configuration.

FIG. 10 is a top plan view of the six-cell beverage box with the telescoping portion positioned in a retracted position; and,

FIG. 11 is a front perspective view thereof.

Those features shown in broken lines form no part of the claimed design.

1 Claim, 10 Drawing Sheets
